US00D895197S

(12) **United States Design Patent** (10) Patent No.: **US D895,197 S**
(45) Date of Patent: ** Sep. 1, 2020

(54) **VAPORIZER DEVICE**

(71) Applicant: **JUUL Labs, Inc.**, San Francisco, CA (US)

(72) Inventors: **Brandon Cheung**, San Francisco, CA (US); **James Monsees**, San Francisco, CA (US); **Kevin Lomeli**, San Francisco, CA (US)

(73) Assignee: **JUUL Labs, Inc.**, San Francisco, CA (US)

(**) Term: **15 Years**

(21) Appl. No.: **29/646,108**

(22) Filed: **May 1, 2018**

(51) LOC (12) Cl. **27-01**

(52) U.S. Cl.

USPC **D27/101**

(57) **CLAIM**

The ornamental design for a vaporizer device, as shown and described.

DESCRIPTION

FIG. 1 is a bottom, front, and right side perspective view of a vaporizer device of our design;

FIG. 2 is a top, rear, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines illustrate portions of the vaporizer device that form no part of the claimed design.

The dash-dot broken lines illustrate boundary lines that form no part of the claimed design. The areas within the dash-dot broken lines form no part of the claimed design.

1 Claim, 5 Drawing Sheets

UNITED STATES PATENT AND TRADEMARK OFFICE
CERTIFICATE OF CORRECTION

PATENT NO. : D895,197 S
APPLICATION NO. : 29/646108
DATED : September 1, 2020
INVENTOR(S) : Brandon Cheung et al.

Page 1 of 1

It is certified that error appears in the above-identified patent and that said Letters Patent is hereby corrected as shown below:

On the Title Page

Item (71) Applicant read:
“JUUL Labs, Inc., San Francisco, CA (US);”
Should read:
--JUUL Labs, Inc., Washington, DC (US)--

Item (72) Inventors read:
“Brandon Cheung, San Francisco, CA (US);
James Monsees, San Francisco, CA (US);
Kevin Lomeli, San Francisco, CA (US)”
Should read:
--Brandon Cheung, San Francisco, CA (US);
Joseph Chun, Berkeley, CA (US);
Kevin Lomeli, San Francisco, CA (US);
James Monsees, San Francisco, CA (US)--

Signed and Sealed this
Sixteenth Day of September, 2025

Coke Morgan Stewart
Acting Director of the United States Patent and Trademark Office
